ATTORNEY.

UNITED STATES PATENT OFFICE

JOSEPH VAN ACKEREN, OF O'HARA TOWNSHIP, ALLEGHENY COUNTY, PENNSYLVANIA,
ASSIGNOR TO THE KOPPERS COMPANY OF DELAWARE, A CORPORATION OF DELA-
WARE

GAS PRODUCER

Application filed August 20, 1929. Serial No. 387,244.

My invention relates to gas producers and particularly to apparatus for removing ash therefrom.

One object of my invention is to provide 5 simple and efficient apparatus for continuously and automatically removing ash from gas generators during their operation.

A further object of my invention is to provide 10 a rotatable ash pan having apparatus carried thereby for removing ash therefrom while the pan is rotating.

A further object of my invention is to provide 15 a rotatable ash pan having apparatus carried thereby and movable therewith for removing ash therefrom in a circular path during the rotation of the pan.

In accordance with my invention, I provide 20 a gas producer having a rotatable ash pan for providing a water seal in accordance with usual practice. The pan is provided with a plurality of ash-lifting devices that rotate with the pan and transfer ash therefrom to a stationary circular trough surrounding the pan. Ash plows that are 25 carried by the pan actuate the ash along the circular trough to an outlet opening from which the ash may be removed by any suitable or usual means.

In the accompanying drawings, 30 Figure 1 is a view, partially in elevation and partially in vertical section, of a gas producer constructed in accordance with my invention;

Fig. 2 is a horizontal sectional view taken 35 on the line II-II of Fig. 1;

Fig. 3 is an enlarged vertical sectional view of a portion of the apparatus of Fig. 1; and

Fig. 4 is an enlarged side view of one of 40 the ash-lifting devices.

A gas producer 1 comprises a stationary portion 2 that is supported on any suitable structure, as, for example, framework 3. The stationary portion 2 of the generator 45 which contains the fire bed indicated at 4 is provided with a charging mechanism 5 and a gas offtake pipe 6.

The bottom of the producer is provided 50 with a rotatable structure comprising an annular ash pan 7 having an inclined outer

side 8. An annular flange 9 connected to the stationary portion 2 extends downwardly into the pan 7 which is partially filled with water to provide a liquid seal between these relatively movable parts.

The ash pan 7 is rotatably mounted on a foundation 10 by means of a ball race 11. The ash pan 7 and the foundation 10 are connected by a water seal formed by a stationary annular trough 12 and an annular 60 flange 13 connected to the ash pan.

The ash pan 7 carries an eccentrically mounted grate 15 that is provided with suitable perforations for admitting air under pressure to the fuel bed. Air is supplied to 65 the grate 15 through a pipe 16 and a vertical duct 17 in the foundation 10.

The ash pan 7 is rotated by a mechanism comprising a relatively large worm gear 18 and a driving mechanism therefor comprising 70 an intermittent mechanism 19 that is actuated by a rod 20 and an eccentric 21 whereby relatively slow motion is imparted to the ash pan 7 and its associated parts.

As is best shown in Figs. 2 and 3, the 75 inclined outer side of the ash pan 7 has mounted thereon a series of rotatable ash-lifting devices 22 having curved arms 23 for lifting ash from the pan 7 outwardly over the edge thereof. Any suitable number 80 of ash-lifting devices 22 may be employed, six being shown by way of example.

The ash-lifting devices 22 are actuated by means of rollers 24 mounted on pins or 85 spokes 25 that extend outwardly from the stationary portion 2 of the producer substantially parallel to the axis of rotation of the ash-lifting devices 22.

An annular trough 27 extends around the periphery of the ash pan 7 in such position 90 as to receive any ash that may be discharged from the ash pan by means of the several ash-lifting devices 22. The trough 27 is provided with an outlet opening 28, into which the ash is actuated by a series of plows 29 95 that are carried by the ash pan 7.

In the operation of the producer, the fuel is gradually consumed by the introduction of air through the grate 15 and the resulting 100 ash descends at a corresponding rate into the

ash pan 7. The latter rotates at a relatively low speed to cause the eccentric grate to agitate the fuel bed and to cause the ash to move gradually downwardly into the ash pan. As the ash pan rotates, the rollers 24 rotate the ash-lifting devices 22 and the latter lift accumulated ash from the bottom of the pan 7 into the annular trough 27.

10 Each of the ash-lifting devices operates continuously throughout the circular path of rotation of the ash pan. At the same time, the ash plows 29 actuate the ash along the trough 27 to the outlet opening 28, from which it may be removed by any suitable means.

15 It will be noted that I have provided a simple and efficient mechanism whereby ash is removed from the ash pan by means operating continuously throughout the rotation of 20 the ash pan. The operation of the ash-lifting devices is brought about by the relative movement between the ash pan and the body of the producer.

25 The operating portions of the mechanism are easily accessible for inspection and repair and are of such rugged nature as to operate for long periods without material wear. The foregoing and other advantages will be apparent to those skilled in the art 30 relating to gas producers.

I claim as my invention:

1. A rotatable ash pan, a rotatable ash-lifting device carried thereby, means operable to rotate said device when said ash pan 35 is rotated, a trough for receiving ash from said device and means for removing ash from said trough.

2. A gas generator comprising a rotatable grate, a rotatable ash pan for containing water and for receiving ash from said 40 grate, an annular receptacle adjacent thereto and having an outlet, and means carried by said pan for continuously transferring ash from said pan to said receptacle and 45 for actuating ash in said receptacle into said outlet.

3. A gas generator comprising a rotatable ash pan, an annular receptacle adjacent thereto and having an outlet, means for transferring ash from said pan to said receptacle, and means movable with said pan for continuously moving ash in said receptacle 50 toward said outlet.

55 In testimony whereof, I have hereunto subscribed my name this 16th day of August, 1929.

JOSEPH VAN ACKEREN.
